WEED EXTERMINATOR

Filed Nov. 27, 1929

Inventor

K.L. Carman,

By Clarence O'Brien, Attorney

UNITED STATES PATENT OFFICE

KENNETH L. CARMAN, OF BRIDGEPORT, NEBRASKA

WEED EXTERMINATOR

Application filed November 27, 1929. Serial No. 410,050.

This invention appertains to new and useful improvements in devices for exterminating weeds and other obnoxious growths in a quick and efficient manner.

The principal object of this invention is to provide a portable hand operated device for applying a poison to weeds in such a manner as to kill the same.

Another important object of the invention is to provide a weed exterminator which because of its extremely simple construction can be manufactured at a cost well within the economic demands of the public.

These and various other important objects and advantages of the invention will become more apparent as the description proceeds.

In the drawings:

Figure 1 represents a side elevational view of the device partly in section.

Figure 2 represents a fragmentary side elevational view of the device.

Figure 3 represents an enlarged fragmentary elevational view of the spout portion of the device.

Referring to the drawings, wherein like numerals designate like parts, it can be seen that the device includes a frusto-conical shaped container 5 closed at its bottom and open at its top. The upper portion of the container is internally threaded to receive the externally threaded plug 6 of the cap 7. This container is adapted to receive a predetermined variety of poison, effective for killing weeds and obnoxious plants.

Projecting outwardly from the cap 7 is an elongated tapering spout 8, which spout is open from its tip inwardly to the point 9. The side walls 10-10 of the spout at the portion outwardly from the point 9 are disposed in parallel relation and converge toward each other in the manner shown in Figure 2. The backwall 11 of the portion of the spout under discussion is provided with a short slit 12 adjacent its ends, while the extremity of the portion is shaped to provide a blunt point 13.

An elongated tube 15 extends through the plug 6 and cap 7 and into the spout 8, where it terminates at one end slightly beyond the point 9 of the spout. The tube 15 terminates

at its opposite end adjacent the bottom of the container 5.

A plug 14 cooperates with the upper end of the tube 15 to fill the space within the spout 8 at the point 9. This plug 14 has a duct therethrough and the upper end of this plug as well as the tube 15 is bevelled on the same plane so that the pad 16 on the oblique end portion 17 of the lever 18 may engage snugly against the same so that there will be no accidental leakage of the fluid from the container and so that air cannot enter the container so as to facilitate leakage thereof.

A band 19 encircles the spout 8 at its intermediate portion and the lever 18 is pivotally secured thereto as at 20. A leaf spring 21 has one end secured to the lower end of the lever 18 while its opposite end is disposed away from the lever 18 for tensional engagement with the spout 8.

It will thus be seen that by inverting the device and disengaging the pan 16 from the outer end of the tube 14, the fluid will pass through the tube and will flow along the trough-like outer end portion of the spout 75 to ultimately pass through the slit 12 and into the opening made into the weed or plant. As the fluid in the container becomes displaced, the resulting space will be filled with air entering through the tube 15.

The container will be filled in a quick and convenient manner by removing the plug 6 and this also allows for the repair or replacement of parts with ease.

Changes in the shape, size and materials 85 may be resorted to in the manufacture of this device, within the scope of the appended claim.

Having described the invention, what is claimed as new is:

A device of the class described comprising a container, a cap for the container, a spout connected with the cap and in communication with the container, said spout terminating in a trough-shaped part having a pointed end, and a slit in the bottom thereof adjacent its pointed end, a tube passing thru the spout into the container and having its outer end located in the trough-shaped part slightly in advance of the outer end of the spout, 100

a short tube in the outer end of the spout and extended into the trough-shaped part, said tubes filling the outer end of the spout and having their outer ends beveled to form an inclined surface, a lever pivoted to the spout and having a pad on its forward end for engaging the said surface to close the outer ends of both tubes, and a spring for normally holding the lever with the pad closing the tubes.

10 In testimony whereof I affix my signature.
KENNETH L. CARMAN.
